UNITED STATES PATENT OFFICE.

SOL C. SHERRY, OF WEST ENGLEWOOD, NEW JERSEY.

MAIL BOX.

Application filed October 11, 1923. Serial No. 667,860.

To all whom it may concern:

Be it known that I, SOL C. SHERRY, a citizen of the United States, and resident of West Englewood, in the county of Bergen and State of New Jersey, have invented certain new and useful Improvements in Mail Boxes, of which the following is a specification.

This invention relates to mail boxes and particularly to the type used in outlying farming districts which are served by rural delivery.

An object of the invention is to provide a mail box of the character described which can be mounted upon a post at a distance from the house and near the roadway.

A further object is to provide in conjunction with the letter box, a signal, whereby the letter carrier will be notified that there are letters within the box for collection, the signal being also used for notifying the owners that mail has been left in the box.

Another object is to provide a box which shall be waterproof and from which the letters cannot be taken by other than those having authority to remove the same.

In the drawings, Figure 1 is a front elevation of my improved mail box. The signal in this instance being set, and the door of the box being closed.

Fig. 2 is a sectional elevation of the box as shown in Fig. 1, the door in this instance being opened.

Fig. 3 is a perspective view of a detail of the letter-drop or flap which closes the entrance to the box and through which the letters are inserted.

Fig. 4 is a side elevation partly in section showing a different mounting of the mail box than that shown in Fig. 2.

Referring to the drawings in detail, 10 denotes the body portion of the box, the top of which is closed by a peaked cover 11, the same being riveted thereto or fastened in any suitable manner.

The upper front portion of the body 10 of the box is provided with an elongated opening 12 which is closed by a door 13, which is pivoted to the sides of the box by the rivets 14, said door being formed to comprise edge fluted flanges 15 which frictionally engage the sides of the box.

At the upper edge of the door there is disposed an outwardly extending spring latch 16, which is bent to lie within a matching resilient member 17, fixedly fastened to

flange 18, or preferably formed as an integral part of flange 18, formed on the top front edge of the body of the box. The latch 16 and member 17 are formed to provide matching openings 19 and 20 through which may be inserted a padlock or other suitable locking means.

The door 13 is provided adjacent its upper portion, with a transverse opening 21, the bottom of said opening being slightly wider than the upper part thereof, said widened part forming a lip 22 which overlies and maintains in position on the bead 23 formed on a flap. The bead 23 rests on the lower edge of the opening in the door and pivotally supports the flap 24. The lower portion 24^a of the flap, which is below the bead 23 is disposed on the outer side of the door 13, the portion 24^b above the bead being offset to lie within the door and rest thereagainst above said opening. The lower end of the flap being the longest will maintain the flap at all times in closed position and the lip 22 formed in the door will prevent the removal of said flap.

On the inner side of the door and near the lower end thereof, there is riveted a suitable money receptacle 25 into which coins necessary for postage of the letters may be held until collected by the postman.

The forward side of the cover 11 is provided with a signal 26 which is pivotally riveted thereto, the rectangular portion 27 being bent to lie in vertical position. The signal 26 is provided with a depression 28 which is adapted to snap over a dowel 29, which acts to maintain the signal in "set" position. The signal may be painted any brilliant color and it is apparent that when letters have been disposed therein by the postman or owners of the box, the signal can be set to show that the mail has been left by the postman or is there for his collection, thereby saving him the time of dismounting from his conveyance and unlocking the box, or the owners from walking to the empty box.

As illustrated in Fig. 2, suitable flange members 30 may be provided at the back-side of the box for engaging the sides and upper end of the post 31 to which the box is secured.

In Fig. 4, the bottom of the box is left open and is formed to fit over the upper end of the post 31, said upper end forming the bottom of the box.

Having thus described my invention, what

I claim as new and desire to secure by Letters Patent, is as follows:—

A mail box comprising an elongated rectangular body portion, a peaked cap fixed to the upper end of said body to form the top thereof and to support a signal and door latch, a mounting member provided with bendable post engaging means secured to the rear of said body and serving to support the whole, an opening in the front of said body portion extending from a point adjacent the aforesaid cap to a point below the vertical center of said box and a cover wider than the

box body and longer than said opening; said cover having rearwardly turned side flaps 15 embracing the body sides and serving as hinges for the cover, said cover also provided with a flap closed mail insertion slot, a coin receptacle, and means for engaging the aforesaid latch on said cap, the whole cooperating 20 to form a box of the character described.

Signed at New York city, in the county of New York and State of New York this 18th day of February, A. D. 1922.

SOL C. SHERRY.
